UNITED STATES PATENT OFFICE

JOHN STADLER, OF MONTREAL, QUEBEC, CANADA

ROTARY PULP SCREEN

Application filed January 2, 1930. Serial No. 418,048.

This invention relates to new and useful improvements in pulp screening devices and the object of the invention is to provide a combined knotter and coarse screening device having comparatively large inlet and discharge openings so that there is no obstruction to impede the movement of the pulp through the screen.

Another object of the invention is to provide a combined knotter and coarse screen, the driving and the supporting mechanism for which are positioned above the level of the stock on which the screen is operating.

According to my invention, I provide a screen which consists of a perforated cylinder with a free inlet opening at one end. This end is provided with a ring which is supported on its internal surface by a plurality of rollers which are positioned above the level of the stock in the screen. The outlet is provided with a casting having spaced arms which are radially disposed to a pivot support on suitable bearings so that there is substantially no obstruction of the lower half 25 of the cylindrical screen. The screen is rotated by mechanism positioned above the level of the stock in the screen. An internal shower pipe of large diameter which is cantilevered from and supported by the inlet casting permits the use of shower water at low 30 pressure in large quantities so that the tailings are free from fine fibres. A suitable form of baffle is spiralled around the inner surface of the screen to provide a fixed path 35 along which the material to be screened or clarified is caused to travel at a rate of speed predetermined to give the best results, according to the character of material being treated. This baffle may be of uniform or 40 irregular pitch, depending upon the character of the material to be screened.

In the drawings which illustrate my invention,

Figure 1 is a part sectional plan view of the screen.

Figure 2 is an end view of the screen shown in Figure 1.

Figure 3 is a sectional side elevation of the screen.

Figure 4 is an end view of the inlet looking in the direction 4-4 of Figure 3.

Figure 5 is a fragmentary sectional plan view showing a modified drive mechanism applied to the outlet end of the screen.

Figure 6 is an end view partly in vertical section and partly in elevation of the modified drive mechanism shown in Figure 5.

Figure 7 is a plan view of a scraper element.

Figure 8 is a sectional view taken along the line 8-8 of Figure 7.

Referring more particularly to the drawings, 11 designates a cylindrical screen which may be provided with reinforcing means 12. The screen at the end 13 is supported internally on a flange ring 14 which is supported on spaced arms 15 radiating from a bearing hub 16. A pin 17 extends outwardly from the hub into a bearing 18 secured to an end support 19 which is positioned above the level of the stock in the screening device and indicated by the numeral 20. The end support 19 is attached to or formed integral with the end frame 21. The other end 22 of the screen is supported internally on a rim 23 formed on a disc 24 having a hub 25. The rim has a flange 27 to which is secured by any suitable means the roller ring 28. The internal surface 29 of the ring rests on the peripheries of the spaced rollers 30 which are secured to shafts 31 rotatably mounted in the bearings 32 and 33. These bearings 32 and 33 rest on the bearing surfaces 34a formed in the inlet casting or such like fixed structure. The rollers are driven by any suitable means. One form of drive is shown in the drawings for illustrative purposes only and consists of bevel toothed wheels 34 secured to the ends of the roller shafts and adapted to mesh with bevel pinions 35 secured to a common shaft 36 rotatably mounted in the bearings 37. A belt pulley 38 driven from any suitable source is secured to the end 39 of the shaft 36. The inlet casting rests on a suitable foundation 40 and is provided with an enlarged inlet opening 41. Separated from the inlet opening by the wall 42 is the shower water inlet 43 the end 44 of which is connected by any suitable means 100

to a vertically disposed shower water conveying pipe, not shown. The end 45 of the inlet 43 has connected thereto a shower pipe 46 extending into the interior of the screen 5 and lying substantially parallel with the longitudinal axis thereof. The shower pipe 46 is cantilevered from the inner end of the inlet casting and is closed at its free end by a cap 47. This shower pipe is positioned above 10 the level of the stock passing through the screen and is provided with perforations so arranged that the shower of water is directed towards the inner surface of the screen at a predetermined angle in order to separate 15 the fine from the coarse material and to free the screen surface of any material that may have a tendency to adhere thereto. A scraper bar 48 is supported between a pair of arms 49 and serves to prevent accumulation of 20 coarse material at the top of the shower pipe 46. One of the arms 49 is secured to the ring 14, while the remaining arm 49 is secured to the disc 24.

It will be seen that in operation a free 25 central opening is provided and that it is comparatively large when compared with the types of screens at present in use. The inlet is combined with the shower pipe inlet and also forms a support for the screen and for 30 the driving mechanism, which is positioned above the stock level. The outlet end is supported on a central pivot and the entire lower half of the screen has substantially no obstruction which would interfere with the 35 flow of tailings therethrough. The screen driving mechanism and supporting means are above the stock level so that there is no danger of same becoming affected by the stock.

40 The shower pipe is cantilevered from the stock inlet and projects into the screen and is of large dimensions permitting the use of shower water at low pressures in large quantities which assures that the tailings are free 45 from fine fibres and if white shower water is used, there is no dilution of the accepted stock as is the case when clear water is used in the shower.

By this arrangement of large inlet and outlet construction, the screen can pass the largest piece of impurities and yet it can be operated with fine perforation on the screen cylinder so that the stock which passes through the screen can be of such fineness that the 55 stock can be passed directly to the fine screen without any further treatment.

A baffle 51 is spiralled around the inner surface of the screen 11 to provide a fixed path of travel along which the material is 60 caused to move in the direction of the screen outlet. This baffle may be of uniform or irregular pitch according to the character of material being screened or clarified. Ordinarily, the spiralled baffle will be of irregular 65 pitch so that the drier material approach-

ing the outlet end of the screen is caused to move at a rate somewhat slower than the fresh material entering the inlet end of the screen.

Figures 5 and 6 disclose a modified arrangement in which the drive mechanism is located at the outlet end of the screen. In this arrangement, the screen supporting pin 52 carried by hub 16 extends into a gear casing 53 formed integral with or secured to the end support 19. The pin 52 rotates in a bearing 54 and is provided with a relatively large gear wheel 55. Gear wheel 55 meshes with a similar gear wheel 56 carried by a shaft 57 journalled in suitable bearings 58; shaft 57 also carries a worm wheel 59 meshing with a worm 60 fixed to a vertically extending shaft 61. The lower portion of shaft 61 is mounted in suitable bearings 62 provided with the casing 53. Shaft 61 passes upwardly, from the casing 53, through a vertical pipe 63, and forms part of a motor 64 carried by the upper end of said pipe. The casing 53 is provided with a removable cover 53a and any suitable means may be provided for maintaining the casing supplied with an adequate amount of lubricating oil. A portion of this oil is picked up by the sides of the gear wheel 55 and delivered to a U-shaped scraper 65 provided with an oil receiving channel 66. The channel 66 is connected by a pipe 67 to the bearing 54 of gear wheel 55 and, by a pipe 68, to the upper bearing 62 of shaft 61. The lower bearing of shaft 61 and the bearings supporting shaft 57 are located below the level of lubricating oil contained in casing 53.

As shown to advantage in Figure 8, the inner walls of the channel 66, lying at opposite sides of the gear wheel 55, are bevelled to provide sharpened edges 69 by means of which the oil is scraped from the sides of the gear wheel 55 and deflected into the channel 66 from whence it flows through the pipes 67 and 68 to lubricate the previously mentioned bearings 54 and 62. The scraper 65 may be supported in the casing 53 by any suitable form of bracket such as that indicated at 70.

Having thus fully described what I now conceive to be the preferred embodiment of my invention, it will be understood that various modifications may be resorted to within the scope and spirit of the appended claims.

Having thus described my invention, what I claim is:

1. In a screen, a perforated cylinder supported on a disc at one end and radially disposed arms at the other end, an inlet passing through the disc, a ring mounted at the inlet end of the screen and roller means engaging the internal surface of the ring and positioned above the maximum level line of the stock in the screen.

2. In a screen, a perforated cylinder, a disc supporting one end of the cylinder, a plurality of arms supporting the other end leaving a clear discharge opening, a bearing 5 from which said arms radiate, and driving and supporting means positioned above the high level line of the stock or material passing through the screen.
3. In a screen, a perforated cylinder, a 10 comparatively large inlet pipe at one end of the screen, radially extending arms supporting the other end and forming a free exit, a bearing from which the arms radiate, a ring secured to the inlet end of the cylinder and roller supporting means engaging with the internal surface of the ring, said roller means being positioned above the central axis of the cylinder.
4. In a screen, a perforated cylinder, a 15 bearing at one end, a central hub having arms radiating therefrom and adapted to support said cylinder end, a bearing pin extending outwardly from the hub into the bearing, an inlet pipe having a comparatively large bore, a disc rotatably mounted on the wall of the pipe and adapted to support the other end of the cylinder, a ring secured to the disc, and rollers engaging with the internal surface of the ring and adapted to 20 support the other end of the screen, said rollers being positioned above the central axis of the cylinder.
5. In a screen, a perforated cylinder, a 25 comparatively large inlet pipe, means engaging with the wall of the pipe and adapted to position said cylinder at one end, a central hub having radiating arms adapted to support the other end of the cylinder, a bearing member, a pin extending from the hub into the bearing a roller race ring secured to the inlet end of the cylinder, rollers adapted to engage with the surface of the ring to support and rotate the cylinder, and means to rotate said screen, said rotating means being positioned above the level of the material 30 passing through the screen.
6. A cylindrical screen having comparatively large inlet and outlet openings, a shower pipe cantilevered from the inlet and 35 extending into the screen, a bearing adapted to support the screen at the outlet end and roller means adapted to support said screen, said roller means being positioned above the central axis of the screen.
7. In a pulp screen, a perforated cylindrical member, an inlet casting at one end thereof, said inlet casting being divided to provide 40 separate passages for the flow of pulp into the screen and also the flow of shower water, a disc surrounding the casting and secured to the screen for positioning same, a hub having radiating arms adapted to support the other end, a pin extending outwardly from the hub, a bearing engaging said pin, a shower pipe secured to the casting and extending 45 into the screen, and roller means adapted to support the screen, said roller means being positioned above the central axis of the cylinder.
8. A coarse screening device including a 50 screen cylinder, a disc fitted in one end of said cylinder and having a rim engaging the inner surface of the cylinder, said disc being also provided with a central opening, and with a flange extending outwardly from said rim, a bearing ring carried by said flange, an inlet casting projecting into the cylinder through the central opening of the disc, rollers arranged within the upper portion of the bearing ring in supporting engagement therewith, said rollers being mounted on bearings carried by the inlet casting, and means for supporting the opposite end of the cylinder.
9. A coarse screening device including a 55 cylinder, a centrally apertured disc having a rim engaging the inlet end of the cylinder, a bearing ring carried by said disc, a relatively large inlet casting projecting into the cylinder through the central opening of the disc, rollers carried upon the upper portion of said casting in supporting engagement with said bearing ring, a second bearing ring having an inwardly extending rim portion fitting within the opposite end of the cylinder, a beam supported to extend transversely across the last mentioned end of the cylinder and means for rotatably supporting the last mentioned bearing ring from said beam.
10. A coarse screening device including a 60 cylinder, a bearing ring secured to the outlet end of said cylinder, means for rotatably supporting said ring, a disc fitted in the inlet end of the cylinder and provided with a central opening, means for rotatably supporting said disc including an inlet casting projecting into the cylinder through the central opening of the disc, a shower pipe extending longitudinally within the cylinder, a scraper located close to the shower pipe and extending in parallel relation therewith, one end of said scraper being supported from said disc and the other end of said scraper being supported from the bearing ring located at the outlet end of the cylinder.
11. A coarse screening device including a 65 screen cylinder, a bearing ring having an inwardly projecting rim portion secured in the outlet end of the cylinder, an end casting, a beam secured to said casting and extending transversely across the outlet end of the cylinder, said beam being positioned above the longitudinal axis of the cylinder and said bearing ring being rotatably supported therefrom, a disc fitted in the inlet end of the cylinder and provided with a relatively large central opening, a suitably supported inlet casting projected into the cylinder through the central opening of said disc, a bearing ring carried by said disc, supporting rollers carried by said inlet casting and serving to 70

support the last mentioned bearing ring, and means for positively rotating one of said bearing rings to impart a corresponding movement to the screen cylinder.

- 5 12. A coarse screening device including a cylindrical screen member, supporting means at the outlet end of the screen member arranged to leave the lower half of said member substantially unobstructed, a centrally apertured disc closing the inlet end of the screen and formed to provide a support for said end, an inlet casting projecting into the screen member through the central aperture of said disc, a bearing ring fixed to rotate with the inlet end of the screen member, supporting rollers journaled on the inlet casting and engaging said bearing ring, and means for imparting rotation to said screen member through the medium of said bearing ring.
- 10 15. In witness whereof, I have hereunto set my hand.
